LENS HOLDER

Ike Rosenbaum, Mount Vernon, Ind.

Application March 7, 1935, Serial No. 9,859

1 Claim. (Cl. 88—47)

This invention appertains to new and useful improvements in lens holders for spectacles and more particularly to spectacles of the frameless type.

5 The principal object of the present invention is to provide a lens holder which will readily hold the lens in a definite fixed position without likelihood of the same becoming displaced or contorted in any manner.

10 During the course of the following specification other important objects and advantages of the invention will become apparent.

In the drawing:

15 Figure 1 represents a front elevational view of the novel fastening means.

Figure 2 represents a sectional view taken substantially on line 2—2 of Figure 1.

Figure 3 represents an enlarged perspective view of the spring and washer.

20 Figure 4 represents a perspective view of the ratchet.

Figure 5 represents a side elevational view of the screw.

25 Referring to the drawing wherein like numerals designate like parts, it can be seen that numeral 5 represents the usual nose piece which is generally of U-shape and which has the lower ends of its leg portions provided with nose engaging contact plates 6. As each retainer is identical, only one is shown in the drawing and in viewing Figures 1 and 2, it can be seen that the lower end of the nose piece leg is provided with a forwardly extending arm 7 which is curved slightly backward as at 8 to merge with the upstanding abutment 9 which in turn is provided with a pair of laterally disposed fingers 10—11, the finger 10 being provided with a threaded bore and while the finger 11 is provided with a smooth bore. These bores being intended to receive the 30 elongated screw 12 which is provided with the tapered head 13, the latter having a laterally disposed lug 14 tapered downwardly.

35 Numeral 15 represents a disk shaped member

having a central opening 16 through which the screw 12 is disposed and ratchet like grooveways 17 radiating from this open center. Numeral 18 represents a washer having a central opening 19 through which the screw 12 is disposed and this washer 18 is provided with a spring shank 20 disposed radially therefrom and having a laterally disposed flange 21 at its free end which bites into the channel 22 in the abutment 9 where the arm 7 merges with the said abutment.

10 Obviously when the screw 12 is disposed through the fingers 10—11 and the lens 23, the lug 14 will engage with the disk 15 and eventually catch one of the ratchet grooves 17 while the spring shank 20 is under tension. In this manner the screw 12 is locked against outward movement and the lens prevented from accidental displacement from the nose piece.

15 While the foregoing specification sets forth the invention in specific terms, it is to be understood that numerous changes in the shape, size and materials may be resorted to without departing from the spirit and scope of the invention as claimed hereinafter.

20 Having thus described my invention, what I claim as new is:

25 In combination, a lens, a nose piece, said nose piece being provided with a lens abutment, said abutment being provided with a pair of laterally disposed fingers between which the lens is disposed, said fingers and lens being provided with 30 registering openings, a screw for disposition through the said opening, a washer on the screw for engaging against one of the fingers, said abutment being provided with a channel, a spring 35 shank extending from the washer and provided with a laterally disposed cleat for engagement into the channel, a ratchet wheel on the screw for engagement against the washer, said screw being provided with a laterally disposed lug 40 adapted for catch engagement with the said ratchet wheel.

IKE ROSENBAUM.
